UNITED STATES PATENT OFFICE.

JAMES A. WOOLSEY, OF DEWVILLE, TEXAS.

DESIGN FOR A WRENCH-HANDLE.

SPECIFICATION forming part of Design No. 35,858, dated April 15, 1902.

Application filed March 14, 1902. Serial No. 98,270. Term of patent 7 years.

To all whom it may concern:

Be it known that I, JAMES A. WOOLSEY, a citizen of the United States, residing at Dewville, in the county of Gonzales and State of Texas, have invented and produced a certain new and useful Design for a Wrench-Handle; and I do declare the following to be a full, clear, and exact description of the invention, such as will enable others skilled in the art to which it appertains to make and use the same, reference being had to the accompanying drawing, and to the letters of reference marked thereon, which form a part of this specification.

15 This invention relates to a new and useful design for a wrench-handle; and it consists in the general shape of an ornamental design which will be hereinafter fully described and illustrated.

20 I have clearly illustrated the design for my wrench-handle in the accompanying drawing, in which I have shown a side elevation of the handle, having an ornamental face.

Reference now being had to the details of 25 the design by letter, A designates the handle of a wrench, which is straight on one edge be-

tween the points indicated by letters B and C and merges into a compound curve between points B and D. One end of the handle is inclined, as at E, with rounded corner 30 F, and the inwardly-inclined end F merges into a notched portion G, and the longitudinal edge opposite the edge between points C and D has an offset K and has a straight-edged portion N parallel with the opposite 35 edge between the points B and C and has its opposite end rounded, as at M.

On the face of the handle are three ornamental fern-leaves. The stems are formed in compound curves, each stem intersecting the 40 stem of the adjacent leaf.

Having thus described my invention, what I claim as new, and desire to secure by Letters Patent, is—

The design for a handle of a wrench substantially as shown and described.

In testimony whereof I affix my signature in presence of two witnesses.

JAMES A. WOOLSEY.
